No. 722,320.

PATENTED MAR. 10, 1903.

W. A. McGREGOR & A. C. SOMERS.
CUSHION DEVICE FOR NIGGER BARS.

APPLICATION FILED JULY 30, 1902

NO MODEL.

UNITED STATES PATENT OFFICE.

WILLIAM A. MCGREGOR AND ALEXANDER C. SOMERS, OF NEAME,
LOUISIANA.

CUSHION DEVICE FOR NIGGER-BARS.

SPECIFICATION forming part of Letters Patent No. 722,320, dated March 10, 1903.

Application filed July 30, 1902. Serial No. 117,678. (No model.)

To all whom it may concern:

Be it known that we, WILLIAM A. MCGREGOR and ALEXANDER C. SOMERS, citizens of the United States, residing at Neame, Vernon parish, Louisiana, have invented a certain new and useful Improvement in Cushion Devices for Nigger-Bars, of which the following is a full, clear, and exact description, such as will enable others skilled in the art to which it appertains to make and use the same, reference being had to the accompanying drawings, forming part of this specification, in which—

Figure 1 is a vertical cross-sectional view of the track-rails of a sawmill-carriage, showing our improved cushioning device in position. Fig. 2 is a top plan view of the cushion device, and Fig. 3 is a sectional view on the line 3 3 of Fig. 1.

This invention relates to a new and useful improvement in cushion devices for nigger-bars or log-turners, the object being to construct a device of the character described, which is composed of a few number of parts, is easily applied in position, requiring no special arrangement or change in existing mills, and one which is easily accessible for adjustment and repair when in position.

With these objects in view our invention consists in the construction, arrangement, and combination of the several parts, all as will hereinafter be described, and afterward pointed out in the claims.

In the drawings, 1 indicates a sawmill-carriage, (shown in dotted lines,) which may be of any ordinary or usual construction, said carriage traveling upon track-rails 2, arranged upon the track-timbers 3.

4 represents the nigger-bar provided with the usual teeth 5, which nigger-bar is designed to be operated in a well-known manner for the purpose of turning a log 6 on the carriage. This nigger-bar preferably works between timbers 8, having facing-plates 9 for the purpose of strengthening and guiding the same in its movements.

In the ordinary operation of the devices above referred to the nigger-bar sometimes trips and throws the log over the knees of the carriage and when relieved of its load will fly inwardly, striking the carriage or the

track on which it runs, doing injury to itself or to said track. It is the purpose of our invention to provide a cushion in the path of movement of the nigger-bar, which will receive the same under such conditions, acting as a buffer in arresting the bar. This cushion device consists of a head 10, slotted vertically in its outer face to accommodate the teeth of the nigger-bar and permits its forward movement without interruption. The face of the nigger-bar rides on the prong ends of this head, as shown, and in ordinary operation the head 10 does not interfere with or affect in any way the movement of the nigger-bar. The head 10 is guided in its horizontal movement by a strap-iron 11.

12 indicates a shank upon which the head 10 is mounted, said shank passing through the opposite rail-timber and having coiled springs 13 and 14 wound about the same and bearing at one end (the inner) against the rail-timber. Collars 15 and 16 are pinned on the shank to afford seats for the outer ends of the springs 13 and 14. A yoke-plate 17 is held in position by bolts 18 for relieving the springs in the adjustment of the shank and its carried head.

The operation of the device is as follows: The nigger-bar is permitted free movement outwardly and inwardly, and in the event of contact with the head 10 in its inward movement the spring 13 will be compressed and the head 10 will cushion the nigger-bar in its inward movement. When the nigger-bar is relieved of pressure, the spring 13 will expand, restoring the nigger-bar to normal position until the collar 16 cooperates with the spring 14 and equilibrium is established between the springs 13 and 14. These opposing springs coöperating with the shank 12 make the head 10 extremely sensitive, so that an efficient cushion or buffer is provided for the nigger-bar, which as it moves inwardly offers an increasing resistance. To adjust the head 10 with relation to the nigger-bar, the bolts 18 are screwed up so as to force the yoke 17 against the collar 16. This moves the bar 12 outwardly and releases spring 13 from collar 15, when collar 15 can be loosened and moved along bar 12 toward spring 14. If it is desired to adjust the head 10 inwardly, the collar 15

is moved the desired distance against its spring 13, after which the bolts 18 are slackened to release the collar 16. To adjust the head outwardly, collar 16 is loosened, relieving spring 14, when the spring 13 will force the bar 12 and its carried head outwardly. Collar 16 is now tightened in its desired position and the yoke moved up against said collar until proper tension is placed on spring 14 or when collar 15 may be loosened until proper tension is placed on the spring 13 and the collar 15 may be again tightened. After the adjustment of the head the bolts 18 are manipulated so as to place the yoke the proper distance behind the collar 16 to permit free play of bar 12 and its carried head. In each instance the spring will recover the bar after actuation and the position being determined by the establishment of equilibrium between the springs.

We are aware that minor changes in the construction, arrangement, and combination of the several parts of our device can be made and substituted for those herein shown and described without in the least departing from the nature and principle of our invention.

Having thus described our invention, what we claim as new, and desire to secure by Letters Patent, is—

30 1. In a device of the character described, the combination with rail-timbers, of a head projecting through one of said timbers, a shank on said head projecting through the other of said timbers, and opposing springs 35 on said shank, one of which is on each side of and coöperates with one of said timbers for restoring the head to central position; substantially as described.

2. In a device of the character described, 40 the combination with rail-timbers, of a head

fastened through one of said timbers, a shank upon which said head is mounted, said shank passing through the other of said timbers, opposing springs one on each side of one of said timbers and on said shank, and a yoke-strap 45 for relieving the springs in the adjustment of the shank and its carried head; substantially as described.

3. In a device of the character described, the combination with a nigger-bar, of a head 50 provided with a vertical channel in its end for accommodating the teeth of the nigger-bar, a shank upon which said head is mounted, a rail-timber through which said shank passes, and opposing springs one of which is on each 55 side of said timber for coöperating with said timber and said shank; substantially as described.

4. In a device of the character described, the combination with rail-timbers, of a channeled head 60 passing through one of said timbers, a shank 12 upon which said head is mounted, said shank passing through the other of said timbers, springs 13 and 14 one of which is upon each side of said last-mentioned timber, collars 15 and 16 on the shank coöperating with said springs, a yoke-plate 17 also mounted upon said last-mentioned timber and coöperating with the collar 16 to relieve the springs in the adjustment of the 65 shank and adjusting-bolts 18; substantially as described.

In testimony whereof we hereunto affix our signatures, in the presence of two witnesses, this 9th day of July, 1902.

WILLIAM A. MCGREGOR.
ALEXANDER C. SOMERS.
